(57) CLAIM

The ornamental design for a wine bottle carrier, as shown and described.

DESCRIPTION

FIG. 1 is a front elevation view of a wine bottle carrier, depicting an embodiment of a new design;
FIG. 2 is a rear elevation view thereof;
FIG. 3 is a right-side elevation view thereof;
FIG. 4 is a left-side elevation view thereof;
FIG. 5 is a bottom view thereof;
FIG. 6 is a top view thereof;
FIG. 7 is another top view thereof wherein the unclaimed design, depicting the snowman's head, is not shown;
FIG. 8 is a side-elevation view of the wine bottle carrier wherein a wine bottle is shown inside the wine bottle carrier;
FIG. 9 is side-elevation view of the wine bottle carrier wherein a wine bottle is shown outside the wine bottle carrier;
FIG. 10 is a front elevation view of a wine bottle carrier, depicting another embodiment of the new design;
FIG. 11 is a rear elevation view thereof;
FIG. 12 is a right-side elevation view thereof;
FIG. 13 is a left-side view thereof;
FIG. 14 is a bottom view thereof;
FIG. 15 is a top view thereof;
FIG. 16 is another top view thereof wherein the unclaimed design, depicting the snowman's head, is not shown;
FIG. 17 is a side-elevation view of the wine bottle carrier wherein a wine bottle is shown inside the wine bottle carrier; and,
FIG. 18 is a side-elevation view of the wine bottle carrier wherein a wine bottle is shown outside the wine bottle carrier. The broken lines in the drawings are for illustrative purposes only and form no part of the claimed design.
